UNITED STATES PATENT OFFICE

2,580,900

PACKAGE FOR TWINE, ROPE, OR THE LIKE

Henry Epstein, Brooklyn, N. Y., assignor of one-third to Mandel E. Epstein and one-third to Morton M. Epstein, both of New York, N. Y.

Application February 23, 1950, Serial No. 145,852

2 Claims. (Cl. 206—59)

1

The present invention relates to package constructions for wound bundles of rope, twine, cord, thread and the like.

An object of this invention is to provide a novel and improved package construction of the character mentioned, which includes a closed box housing a bundle of rope, twine or the like therein, whose free end is positioned through an opening in the box structure, and particularly affording means whereby said free end of the rope or twine is secured in such manner in making up of the package for shipment, that it will remain in fixed position on the package and sealed therein, with the further feature that when the rope or twine is desired to be used, such free end thereof is made accessible and withdrawn from the box upon ripping off a certain sealing strip employed in making up the package.

Another object hereof is to provide a novel and improved package of the type set forth for a wound bundle for rope, twine or the like; the package to have an opening only for the free end of the rope or twine and affording means whereby said free end will not become "lost" while the package remains unopened.

A further object hereof is to provide a novel and improved package construction of the nature described, which makes it unnecessary to wind rope or twine on wooden reels as is the common practice, and hence effects a substantial saving and eliminates the use of reel stands.

Another object of this invention is to provide package constructions which are novel and improved for the purposes mentioned, reasonably cheap to manufacture, convenient in use and efficient in carrying out the purposes for which they are designed.

Other objects and advantages will become apparent as this disclosure proceeds.

In the accompanying drawings forming part of this application, similar characters of reference indicate corresponding parts in all the views.

Fig. 1 is a perspective view of a box structure housing a wound bundle of rope, twine or the like. The free end of the rope or twine is shown extending from the box through a slot in the box cover. The package so made up is either ready for use, or ready to be sealed in accordance with the teachings of this invention.

Fig. 2 is a top plan view of the box fitted with an element whose function it is to avoid movement of said free end back into the box.

Fig. 3 is a view showing all of Fig. 2 plus a

2

sealing strip applied onto the body of the box to close the mentioned slot and made to fixedly adhere to the free end of the rope or twine.

Fig. 4 is a top plan view of the package, showing the sealing strip partially ripped off the box body and carrying the free end of the rope or twine in position accessible to be pulled. This view really shows the first thing a user will do when it is desired to start using the rope or twine packaged.

Fig. 5 is a top plan view of the package, showing the sealing strip entirely ripped off the box body and carrying along with it the retaining strip shown in Fig. 2, and of course, carrying the free end of the rope or twine in position accessible to be pulled.

Fig. 6 is akin to Fig. 3, showing a modified construction.

Fig. 7 shows the sealing strip used in Fig. 6, 20 ripped off the body of the box structure.

In the drawings, the numeral 15 designates a box having a flat top 16 and a flat bottom 17, which are preferably flanged and glued onto the body portion 18. The box may be of any other 25 suitable construction and its shape may be other than octagonal as shown. This box, made of corrugated board having flat facings or of heavy cardboard or else of other suitable stiff sheet material, houses a wound bundle 20 of rope, twine or the like; the winding being what is known as the coreless tube type, made of a single length wound in concentric coils and adapted to be unwound preferably from center outwardly, first the most inner coil, then the 30 next coil and so on until the entire bundle is unwound. The box top 16 is provided with a radial slot 19, preferably commencing at the center of the box top, through which slot the free inner end 21 of the rope or twine extends 35 out of the box. The bundle 20 snugly fits the box body 18. Suitable indicia 22 are provided along the slot 19, which among other things is taught in my previous invention in this art identified in my application for patent now 40 pending under Serial No. 119,189 filed October 1, 1949.

To prepare the package for shipment, I paste a strip 23 across the slot 19, near the center of the box top and so that it shall engage the 50 withdrawn end portion of the rope or twine as is shown in Fig. 2. Then I lay such end piece 21 over said strip 23 and into and along said slot. The height of the bundle 20 in the box 15, is preferably such that when the end piece 21 is so laid in and along the slot 19 atop the bundle

20, such end piece shall be substantially flush with the top surface of the box top 16. Now I paste a strip 24 onto the box top to cover the entire slot 19. It is evident that said strip having adhesive substance on its entire under surface, will attach itself to both the strip 23 and the rope or twine end piece 21 and seal the package.

The sealed package, ready for shipment or storage, is shown in Fig. 3. It is important to note than in handling of the package, the bundle 20 may shift therein. Such bundle movement, if no retaining strip as 23 is provided, would cause the end piece 21 of the rope or twine to shift within the box, away from the region of the slot 19, and be thereupon unaccessible or as is usual to say in the parlance of the trade, that the end is "lost." The strip 23, across the slot 19 as near as is possible to the center of the box and being overlapped by the free end piece 21 of the rope or the like, prevents the aforesaid objectionable occurrence.

When it is desired to start use of the rope or twine, the strip 24 is pried from and ripped off the box top as shown in Figs. 4 and 5. The end piece 21 will adhere to the strip 24 and be readily accessible to the user, and the strip 23 will also come off attached to the strip 24, because of the greater adhesion existing between said strips than there was between the ends of the strip 23 and the box top. If it happens that the strip 23 remains in condition as in Fig. 2 when strip 24 is ripped off as in Fig. 5, then upon commencement of pull on the end piece 21 to withdraw a length of rope or twine from the package, said strip 23 would break anyway. Hence where there is no need to protect the package from moisture, dampness or dust, a strip 25 may be used instead of strip 24 to cover and adhere only to the free end portion of the end piece 21 as shown in Fig. 6. When such strip 25 is ripped off, the end piece 21 will be lifted with it and be accessible.

The box 15 may be of corrugated board, cardboard or the like. The strips 23 and 24 may be gummed paper tape, pressure sensitive tape, or the like, and if desired the strips 24 and 25 may be gummed printed labels. Also a wire staple may be used instead of the paper strip 23, which embodiment is well understood and needs no illustration.

This invention is capable of numerous forms and various applications without departing from the essential features herein disclosed. It is

therefore intended and desired that the embodiments shown herein be deemed illustrative and not restrictive and that the patent shall cover all patentable novelty herein set forth; reference being had to the following claims rather than to the specific description herein to indicate the scope of this invention.

I claim:

1. In an article of the character described the combination of a bundle formed of a continuous rope, twine or the like, wound about an axis and having an exposed end piece to be pulled to unwind the bundle, a box housing the bundle and provided with a slot in a wall thereof intersected by said axis; said slot being substantially radial with respect to said axis; the said end piece of the rope, twine or the like being positioned along the slot, a first strip of sheet material pasted on the box across a part of the slot and positioned where it crosses the slot, between the bundle and the said end piece of the rope, twine or the like; the said end piece extending from the bundle and across and beyond said first strip and a second strip of sheet material pasted on the box across the slot and adhering to said end piece of the rope, twine or the like and also overlapping and adhering to the first strip, whereby when said second strip is ripped off the box from across the slot, the free end piece of the rope, twine or the like, will be carried along with the second strip and said first strip will rip off and be carried along by said second strip; the commencement of the ripping off of the first strip being later than the commencement of the ripping off of the second strip.

2. An article as defined in claim 1, wherein the second strip covers the entire slot.

HENRY EPSTEIN.
